[57] **CLAIM**

The ornamental design for a feeder for an animal cage, as shown and described.

DESCRIPTION

FIG. 1 is a perspective view of a feeder for an animal cage constructed in accordance with the invention;
FIG. 2 is a top plan view of the feeder for an animal cage depicted in FIG. 1;
FIG. 3 is a side elevation view of the feeder for an animal cage depicted in FIG. 1, the opposite side elevational view being identical thereto in mirror image;
FIG. 4 is a front elevational view of the feeder for an animal cage depicted in FIG. 1;
FIG. 5 is a rear elevational view of the feeder for an animal cage depicted in FIG. 1;
FIG. 6 is a bottom plan view of the feeder for an animal cage depicted in FIG. 1; and
FIG. 7 is a cross-sectional view taken along line 7—7 of FIG. 4.
